UNITED STATES PATENT OFFICE.

WILLIAM LONSDALE AND WILLIAM H. LONSDALE, OF GRAND CROSSING,
ILLINOIS.

CURLING-TONGS.

SPECIFICATION forming part of Letters Patent No. 351,331, dated October 19, 1886.

Application filed June 1, 1886. Serial No. 203,729. (No model.)

To all whom it may concern:

Be it known that we, WILLIAM LONSDALE and WILLIAM H. LONSDALE, citizens of the United States, residing at Grand Crossing, in 5 the county of Cook and State of Illinois, have invented certain new and Improved Curling-Tongs; and we hereby declare the following to be a full, clear, and exact description of the same.

10 Our invention relates to the article of toilet used for curling and crimping the hair, whether on the head or the face. It is our object to provide such a device by the novel construction of which the article shall be comparatively inexpensive to manufacture, but 15 eminently efficient for its purpose.

Our invention consists in the construction hereinafter described and claimed.

In the drawings, Figure 1 is a side elevation of our improved curling-tongs, showing the clamping portion in its normally-closed condition; Fig. 2, a similar view showing the clamping portion opened; Fig. 3, a similar view to that shown in Fig. 1, but partly in 25 section; Fig. 4, a cross-section taken through the clamping portion, and Fig. 5 a sectional view on the line 5-5 of Fig. 2.

A is the handle, formed of metal, preferably steel wire, of suitable size, bent to cross itself, 30 as shown at *x*, and form a jaw, *r*, of the same or substantially the same cross-section as the wire of the handle, and the part *g*, upon which the larger clamping-jaw *B* is secured, preferably by drilling a hole in its end, heating 35 it and forcing into the hole the end *q*, upon which the jaw *B* shrinks in cooling, and the latter is grooved, as shown at *p*, Fig. 4, to receive the jaw *r*.

To use the device, the jaws are heated in the 40 common way, and the handle is compressed in the hand, whereby the jaws *B* and *r* are separated equally throughout their entire lengths to receive between them the hair to be curled, which they clamp on relaxing the pressure of 45 the hand, holding the hair firmly to permit it to be rolled to produce the curl.

This device which obviously, may also be used to advantage as crimping-tongs, presents

very great advantages, which are absent from similar devices of different construction. It 50 is made without a joint, and the automatic clamping effect is produced without the use of an extra spring, commonly provided in other devices of this nature near the point of crossing or pivotal point. The effect of a spring 55 being in our device produced solely by the handle itself, the relative dimensions in cross-section of the jaw *B* and handle are such as to prevent the heat in the former from readily transfusing itself over the handle, and thereby 60 causes the part *B* to retain its heat for a long time, and with its great effectiveness in accomplishing its purpose it combines simplicity, cheapness of construction, and durability. 65

What we claim as new, and desire to secure by Letters Patent, is—

1. Curling-tongs comprising, in combination, a handle, *A*, formed of springy metal, bent and crossed upon itself to produce a 70 clamping-jaw, *r*, substantially equal in cross-section to the metal forming the handle, and a grooved clamping-jaw, *B*, greater in cross-section than the clamping-jaw *r*, parallel to it and fitting into its groove, whereby the device 75 is formed without a joint, and the parallel clamping-jaws are movable equally throughout their entire lengths, substantially as described.

2. Curling-tongs comprising, in combination, a handle, *A*, formed of springy metal, bent and crossed upon itself to produce a clamping-jaw, *r*, equal in cross-section to the metal forming the handle, and an end, *q*, and a grooved clamping-jaw, *B*, secured upon the 85 end *q*, and greater in cross-section than the clamping-jaw *r*, parallel to it and fitting into its groove, whereby the device is formed without a joint, and the parallel clamping-jaws are movable equally throughout their entire 90 lengths, substantially as described.

WILLIAM LONSDALE.

WILLIAM H. LONSDALE.

In presence of—

HENRY HUDSON,
J. W. DYRENFORTH.
